UNITED STATES PATENT OFFICE.

ALFRED CURRIER, OF GRAND RAPIDS, MICHIGAN.

CASTER.

SPECIFICATION forming part of Letters Patent No. 436,698, dated September 16, 1890.

Application filed March 27, 1890. Serial No. 345,587. (No model.)

To all whom it may concern:

Be it known that I, ALFRED CURRIER, of Grand Rapids, in the county of Kent and State of Michigan, have invented a new and useful Improvement in Casters; and I do hereby declare that the following is a full, clear, and exact description of the same.

My invention above mentioned relates to casters of that class commonly used upon furniture.

My object in making the said invention is mainly to reduce the cost of the article, which is made and used in immense numbers, and I have also secured improved quality of durability—a very effective connection between the parts.

The invention consists in the improved connection between the spindle of the caster-wheel frame and the socket in which the spindle is inserted.

The invention is illustrated in the accompanying drawings, in which—

Figure 1 represents a side elevation of the spindle with the connecting device thereon. Fig. 2 shows a like view of the same in place within the socket, part of the shell being broken away to show the connecting device in position. Fig. 3 shows a side elevation of a modified form of the device on its spindle, and Fig. 4 represents the same one-quarter turned. Fig. 5 is a section on line xz , Fig. 3.

In the drawings, A represents an ordinary form of socket, which may stand for any socket suitable to hold the spindle of a caster-wheel. For the purposes of this invention it may have a plain or smooth interior surface, or may be provided with a circumferential groove, such as that shown at a . The spindle B, which carries the wheel D, is fitted to the socket so as to turn therein in the usual manner, and does not differ from ordinary spindles of its class, except that it requires a circumferential groove, as shown in Figs. 1 and 2 at d and in Figs. 3 and 4 at e , this groove being for the purpose of holding the wire spring-connection; but spindles of this class have been heretofore made with such grooves, and this forms no part of my invention.

Referring to Figs. 1 and 2, which show what I regard as the best form of my invention, it will be seen to consist of a wire wound around

the neck of the spindle and having the ends crossed or interlocked and diverging from the spindle. The wire, as shown, and most conveniently, is of one piece, and is necessarily elastic. I have shown it as wound twice about the neck, or in the groove, this being not essential, but for greater security and better effect, as hereinafter explained. After being thus wound one or more times the ends are brought together and crossed, as shown at f , to form arms, and then are bent in a divergent direction from the spindle. These arms g , when the spindle with them is inserted in the socket, bear against the wall of the socket and hold the spindle therein. This hold may be by frictional contact alone against plain walls, as I have found by trial; but there may be a circumferential groove, as shown, in which the laterally-bent ends of the arms rest. This gives a stronger hold, and the laterally-bent ends afford a greater frictional bearing-surface. When compressed, the arms yield inwardly, and by reason of their leverage over the fulcrum of their crossing they gain some elasticity also from the coils about the spindle. A second and lower groove h may be made in the spindle for the bent ends to rest in when entering the socket.

In Figs. 3 and 4 the modification shown consists of a similar piece of spring-wire, the ends of which are wound upon the spindle, having a wider circumferential groove. A bearing arm or loop m is left, and the ends of the wire (it being a single piece) are brought around and crossed upon the wire of the bearing-arm and bent to interlock, as shown at n . The bearing-arm is then bent aside, but is left projecting outside of the range of the walls of the socket, so that when the spindle with the wire spring is inserted in the socket the spring will bear with sufficient tension.

I have thus shown two forms; but the spring-wire may be applied to the spindle in various ways not necessary to show. It is essential that the spring-wire be attached to the spindle and that some part of the wire diverge therefrom so as to bear upon the wall of the socket.

I claim—

1. In combination with a caster-spindle, a spring-retainer therefor, consisting of a wire wound about the said spindle and having an arm projecting from the spindle, said arm having a bearing at its outer end to engage the wall of the socket, substantially as described.
2. In combination with a caster-spindle, a spring-retainer, consisting of a wire wound about the said spindle and having arms *g g*,

diverging and having bearings at their outer ends to engage the interior of the socket on opposite sides, substantially as described.

In testimony whereof I have signed my name to this specification in the presence of 15 two subscribing witnesses.

ALFRED CURRIER.
